FIG. 1

FIG. 2

FIG. 3

To all whom it may concern:

Be it known that I, Jean O. Reinecke, a citizen of the United States and a resident of Chicago, in the county of Cook and State of Illinois, have invented a new, original, and ornamental Design for Weighing Scale, of which the following is a specification, reference being had to the accompanying drawing, forming a part hereof.

Fig. 1 is a perspective view of a weighing scale embodying my new design;

Fig. 2 is a side elevational view of the weighing scale wherein parts of the scale have been broken out for convenience of illustration; and

Fig. 3 is a front elevational view of the weighing scale.
I claim:

The ornamental design for a weighing scale, as shown.
